CLAIM

I claim the ornamental design for a planter pot attachment, as shown and described.

DESCRIPTION

FIG. 1 is a perspective view of a planter pot attachment showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a perspective view thereof with foldable tabs folded down;

FIG. 9 is a perspective view thereof; and,

FIG. 10 is a bottom perspective view thereof.

The broken lines in FIGS. 9 and 10 are included to show another planter pot attachment, and other environmental features that form no part of the claimed design.
